UNITED STATES PATENT OFFICE.

THOMAS PICKERING DROWN, OF BOSTON, MASSACHUSETTS.

DESIGN FOR A PIECE OF CONFECTIONERY.

SPECIFICATION forming part of Design No. 31,016, dated June 13, 1899.

Application filed May 15, 1899. Serial No. 716,962. Term of patent 7 years.

To all whom it may concern:

Be it known that I, THOMAS PICKERING DROWN, of Boston, county of Suffolk, and State of Massachusetts, have invented and 5 produced a new and original Design for a Piece of Confectionery, of which the following description, in connection with the accompanying drawing, is a specification, like letters on the drawing representing like parts.

10 The drawing is a plan view of a piece of confectionery embodying the design.

The piece of confectionery is in the general shape of a human hand, the side shown representing the back of the hand with thumb 15 *a* and fingers *b* molded or cut in the surface. The leading feature of the design consists in

the representation of the hand with a finger-ring *c* extending loosely around one of the fingers, the said finger being separated from the main portion of the piece of confectionery, 20 as indicated at *d*.

I claim—

The design for a piece of confectionery, substantially as herein shown and described.

In testimony whereof I have signed my 25 name to this specification in the presence of two subscribing witnesses.

THOMAS PICKERING DROWN.

Witnesses:

HENRY J. LIVERMORE,
NANCY P. FORD.
